UNITED STATES PATENT OFFICE.

SIGVARD SIMONSON, OF BUTLER, PENNSYLVANIA, ASSIGNOR OF ONE-HALF TO
WENDEL JOHN MEYER, OF BUTLER, PENNSYLVANIA.

COUPLING AND BUFFING MECHANISM.

1,174,094.

Specification of Letters Patent. Patented Mar. 7, 1916.

Application filed March 5, 1915. Serial No. 12,266.

To all whom it may concern:

Be it known that I, SIGVARD SIMONSON, a resident of Butler, in the county of Butler and State of Pennsylvania, have invented a new and useful Improvement in Coupling and Buffing Mechanism, of which the following is a specification.

This invention relates to a coupling and buffing mechanism for railway cars.

10 The object of the invention is to provide a coupling and buffing mechanism so constructed that the line of stress in the draft beams under impacts sufficient to exceed the capacity of the draft gear is parallel with 15 the lines of buffing and tugging stresses.

With draft and coupling mechanism as usually constructed, when an impact sufficient to exceed the capacity of the draft gear is applied to the coupler, the inner face 20 of the coupler head strikes a buffer casting or striker plate, on the end of the car under-frame. As the head is provided with only one buffing horn (usually the top), forces at an angle to the axial line of the draft 25 rigging are set up by the impact of this horn with the striker plate, and these forces have a greater tendency to wrench or buckle the draft beams or other parts of the car structure than were the forces concentric with the 30 axis of the said draft sills. Such angular forces are avoided in the present construction by providing the inner face of the coupler head with a plurality of buffing horns, or a horn extending all around the coupler 35 head, so arranged that when there is an impact between the coupler head and buffer casting, the force of such impact is distributed evenly about the axial line of the rigging. The present construction is also 40 so arranged that no angular forces are set up upon either straight tracks or upon curves, should an impact between the coupler and buffer head occur.

In the drawings, Figure 1 is a horizontal 45 section through the buffer casting and draft beams showing the coupler and parts of the draft gear in plan; Fig. 2 is a vertical sectional view of the same; Fig. 3 is an end elevation of the outer face of the coupler; Fig. 4 is a view similar to Fig. 1 but showing a different form of buffer casting and coupler head; Fig. 5 is a side elevation of a coupler showing a modified arrangement of the buffing horns upon the head thereof; and Fig. 6 is a similar view showing a single

horn extending entirely around the coupler head.

The device in its general features follows the usual elements of draft and coupling mechanism of standard Master Car Builders' type. The draft rigging is secured between draft sills 1 located, as is usual in the underframe or on the under part of the car body, and comprises the draft gear which consists of the usual elements, here shown as 60 draft yoke 3, follower plates 4 and 5 and lugs 6 and 7 against which the follower plates 4 and 5 impinge, respectively, during different conditions of use. A suitable draft spring, or friction gear mechanism of the 65 customary form will also be provided, but is not shown. The coupler 8 is provided with the usual knuckle 9 and shank 10 extending into the draft rigging. The locking means for the knuckle is not shown. To 70 the forward ends of the draft beams is secured the buffer casting or striker plate 11 against which the inner face of the coupler head strikes when cars are brought together under strong impact, so that too 75 great a compression of the springs between the follower plates is avoided, and the blow is taken directly by the car frame, as has been mentioned above. If only one buffing horn on the coupler head is provided, upon 80 the upper face of the coupler, forces at an angle to the axial line of the coupler shank 10 and draft gear 3 are set up, as mentioned above. In order to distribute the forces of 85 such impacts about the axial line of the draft gear and to avoid the tendency to buckle which occurs when a force at an angle to such a line is set up, the inner face of the coupler is provided with a plurality of buffing horns 12 arranged uniformly 90 around the central axial line of the coupler and draft gear. These may be either upon the corners of the head at the inner face thereof, as shown in Figs. 1 and 3, or at the center of two opposite sides of the coupler 95 head, or at the center of each side of the coupler head, as shown in Fig. 5. In its simplest form and as arranged for use upon cars where curves in the track are not numerous, the outer face 13 of the buffer 100 casting or striker plate and the striking surfaces 14 of the buffer horns may be flat, as shown in Fig. 5. In order that the same result may be obtained when strong impacts are received while on curves, the face 13 of 105 110

the buffer casting or striker plate 9 is formed on the arc of a circle, and the contacting faces 14 of the buffering horns 10 are upon an arc of a circle of equal radius, as shown in Fig. 1. Moreover, the inner end 15 of the coupler shank is preferably rounded on an arc of a circle of radius concentric to that upon which the face of the horns 12 of the coupler are formed, and a correspondingly curved seat is formed in the face of the forward follower plate, so that their engagement corresponds to that between the buffering horns and striker plate. By this arrangement when the car is on a curve, the coupler can swing outwardly, and if an impact sufficient to cause the coupler head to impinge against the striker plate is delivered to the car the thrust upon the coupler is distributed by the curved faces of the coupling horns and striker plate and by the rounded engagement between the coupler shank 10 and forward follower plate 5 so that it is delivered to the draft sills as a straight blow along their axial line, and no angular stresses are set up. Instead of a plurality of horns arranged uniformly about the axis of the draft gear, the outer end of the coupler head may be provided with a single horn extending entirely therearound and having a face cut on an arc of the same circle as the face of the striker plate.

This invention entirely does away with all angular stresses which would add to the compression or tensile stresses in the draft sill or other parts of the car structure and distributes the stresses around the central axis, and by means of simple modifications which add practically nothing to the expense of manufacture. The improvements, moreover, are such that they can be applied to the standard Master Car Builders' coupler without changing the form or proportion of the usual parts, so that coupling mechanism made according to this invention will engage with and be interchangeable with all Master Car Builders' couplers now in use.

It is to be understood that the present invention is not limited to the specific forms disclosed in the drawing and description, and that no limitations other than those incorporated in the claims are to be applied thereto.

What I claim is:—

1. In coupling and buffering mechanism, the combination with a yielding draft gear, of a striker plate having a coupler shank opening and buffer surfaces above and below said opening, of a coupler shank extending through said opening and having a swinging engagement with the draft gear, a coupler head on said shank, and buffer horns on said coupling head above and below the axis of said coupler shank and symmetrically arranged relative thereto and presenting buffer

faces at the inner end of said coupler head equidistant from the striker plate when out of contact therewith.

2. In coupling and buffering mechanism, the combination with a yielding draft gear, of a striker plate having a coupler shank opening and buffer surfaces above and below and to the sides of the axis of said opening, of a coupler shank extending through said opening and having a swinging engagement with the draft gear, a coupler head on said shank, and buffer horns on said head located above, below and to the sides of the central longitudinal axis of said coupler shank and symmetrically arranged relative thereto and presenting buffer faces at the inner face of said coupler head equi-distant from the striker plate when out of contact therewith.

3. A coupling and buffering mechanism, comprising a striker plate having a curved outer surface, draft means, a coupler shank having a swinging engagement therewith, a coupler head on said shank, and a plurality of buffering horns disposed each at a corner of said coupler head and having faces cut on an arc of the same circle as the face of the striker plate.

4. A coupling and buffering mechanism, comprising a striker plate having a curved outer surface, draft means, a coupler shank having a swinging engagement therewith, a coupler head on said shank, and a plurality of buffering horns spaced equal distances from the central line of said coupler head and having faces cut on an arc of the same circle as the face of the striker plate.

5. A coupling and buffering mechanism, comprising draft means, a coupler shank extending into said draft means and having connection therewith, the inner extremity of the coupler shank being formed on the arc of a circle and the contacting portion of the draft means being similarly dished to engage therewith, a striker plate having an outer face curved on an arc of a circle concentric with the dished portion of the draft means, and a coupler head provided on its inner face with buffering means arranged at every point of contact with the striker plate to present thereto a surface cut on an arc of the same circle as the outer face of the striker plate.

6. A coupling and buffering mechanism, comprising draft means, a striker plate having a curved outer face, a coupler head provided with a plurality of buffering horns disposed thereon at equal distances around the central axial line of said draft means and having faces cut on an arc of the same circle as the face of the striker plate, and a coupler shank extending into the draft means and having connection therewith, the inner extremity of the coupler shank being rounded on an arc of a circle concentric with the circular face of the coupler horns,

and the contacting part of the draft means being similarly dished to engage therewith.

7. A coupling and buffing mechanism, comprising draft means, a striker plate having a curved outer face, a coupler head provided with a plurality of buffing horns disposed at the corners thereof and spaced equal distances around the central axial line of said draft means and having faces cut on an arc of the same circle as the face of the 25
5 striker plate, and a coupler shank extending into the draft means and having connection therewith, the inner extremity of the coupler shank being rounded on an arc of a circle concentric with the circular face of the 30
10 coupler horns, and the contacting part of the draft means being similarly dished to engage therewith.
8. A coupling and buffing mechanism, comprising draft means, a striker plate having
15
20

a curved outer face, a coupler head provided with a plurality of buffing horns spaced equal distances around the central axial line of said draft means and having faces cut on an arc of the same circle as the face of the 25
5 striker plate, and a coupler shank extending into the draft means and having connection therewith, the inner extremity of the coupler shank being rounded on an arc of a circle concentric with the circular face of the 30
10 coupler horns, and the contacting part of the draft means being similarly dished to engage therewith.

In testimony whereof, I have hereunto set my hand.

SIGVARD SIMONSON.
